CYLINDER DOOR CONSTRUCTION

Frank A. Gerlach, Cincinnati, Ohio, assignor to
The American Laundry Machinery Company,
Norwood, Ohio, a corporation of Ohio

Application September 7, 1935, Serial No. 39,544

2 Claims. (Cl. 220—32)

My invention relates to washing machine drums or cylinders, including doors for such cylinders, and improved means for maintaining the doors in a tightly sealed relationship with the drum during the washing operation.

In cylinders or drums utilized in washing machines it is essential to maintain the doors tightly sealed with respect to the body of the cylinder during the washing operation; otherwise, parts of the fabric may become embedded or caught in openings or crevices between the door and the cylinder and stretched or torn during the washing operation. Since the drum is continually employed during the life of the washing machine, some wear of mating parts is inevitable and, consequently, it is also desirable to provide some means to compensate for such irregularities so that the door may be maintained in tightly sealed relationship with respect to the body of the cylinder during the life of the washer.

It is therefore an object of my invention to provide an improved door construction for washing machine cylinders or drums which may be maintained in a tightly sealed position with respect to the cylinder or drum. Another object is to provide improved sealing means for washing machine cylinders or drums, including doors of the multiple type in which the lower door may be employed as an unloading shelf during the removal of the fabric, and the upper door is so arranged that the lower door will be sealed in a tightly closed position with respect to the cylinder walls during the washing operation. A further object of my invention is to provide improved means for maintaining the doors of washing machine cylinders in a tightly sealed position, including latching mechanism and means for adjusting such mechanism whereby the door may be maintained in sealed relationship with the cylinder body during the entire life of the washer.

My invention will be better understood by reference to the accompanying drawings in which Fig. 1 is a front elevational view showing the doors in closed position; Figs. 2, 3, 4, 5 and 6 are cross sectional views on lines 2—2, 3—3, 4—4, 5—5 and 6—6 respectively of Fig. 1; Fig. 7 is a detail sectional view on the line 7—7 of Fig. 1; and Fig. 8 is a cross section on the line 8—8 of Fig. 2.

Referring to the drawings, the washing machine cylinder is of the usual construction including a plurality of staves 1 provided with recesses which receive the end plates 2. The cylinder is surrounded adjacent its ends with suitable metal bands 3 and 4 and is provided with trun-

nions 5 and 6. The stave adjacent the upper sill projects downwardly as indicated at 7 into the interior of the cylinder to act as a lifting rib and to form a strong support for the upper hinge leaf 8. Sills 9 and 10 likewise project a short distance into the cylinder and are provided with recesses 11 and 12, respectively, into which portions of the doors extend.

Staves 1 adjacent each side of the door are provided with recesses into which is fitted substantially U-shaped metal panels 13 having outwardly extending flanges 14 which are fixed to the staves 1 in any suitable manner, such as by means of screws 15.

As illustrated, the opening is adapted to be closed by a main door 16 which is shown for purposes of illustration as the upper door, and a secondary door 17, shown as the lower door. The staves in the upper door are maintained in assembled relationship by plates 18 and 19 which are fixed to the staves by means of bolts 20. The plates extend over the sides of flanges 2 and contact with resilient strips 21 located in the U-shaped panel 13. At their upper ends the metal plates are provided with knuckles 19a which interfere with knuckles 22 in the upper leaf of the hinge. The knuckles are held in position by tapered pins 23 provided with threaded nuts 23a so that any wear upon the knuckles or bolts may be adjusted. The upper leaves of the hinges are attached to the adjacent stave and the sill 9 by bolts 24 and 25 respectively. Bolts 25 pass through one flange of an angle iron 26, the other flange of which fits into the recess 11 and forms a smooth metal surface against which the upper door bears in its closed position.

The lower door is attached to the frame of the cylinder by hinges, the leaves 27 of which are attached to sill 10 and the stave adjacent thereto by means of bolts 29 and 30 respectively. Bolts 30 pass through one flange of an angle iron 31, the other flange 32 of which fits in the recess 33 and forms a bearing for the end of the door. It will be noted that sill 10 is also bevelled inwardly as indicated at 34 to form a support for the lower edge of the door 17. The leaf 27 of each of the lower hinges is provided with a knuckle 35 which fits between lugs 36 projecting outwardly from the bottom of the door and tapered bolts 38, provided with nuts 39, serve as pivots on which the door is rotated. Bolts 38 are tapered and may accordingly be adjusted at desired intervals to take up any play caused by wear. Door 17 is provided with outwardly extending shoulders or flanges 17a at each end which extend over the adjacent

staves and the lower door is provided with a cover having downwardly extending side walls which form recesses for the hinges of sufficient length to permit nuts 39 to be adjusted.

- 5 The upper door is provided at its lower portion with a metallic member having a flat bottom 40, a substantially vertical portion 41 which terminates in an outwardly extending flange 42, and an upwardly inclined flange 44 which forms the 10 bevelled bottom edge of the upper door. The outwardly extending flange 42 fits in a recess 43 in the lower wooden stave of the door. The lower door is also preferably formed of metal and consists of a bottom portion 45 having an upwardly 15 extending bevelled flange 46 forming an edge which has the same, or substantially the same, degree of inclination as the flange 44 on the upper door.

The face of the flange 44 is provided with an 20 undercut groove 50 in which is inserted a strip 51 which is preferably formed of rubber or other resilient material. The resilient strip 51 extends beyond the confine of groove 50 and is provided with flanges 52 and 53 which extend along the 25 face of the flange 44 and are adapted to bear against flange 46 on the lower door when the doors are in closed position. From Fig. 5 of the drawings it will be noted that the inclined or bevelled face 46 of the lower door is also adapted 30 to bear against inclined face 37 on the outer casing 54 of the washing machine when the lower door is in open position. The door therefore serves as an unloading shelf between the inner cylinder and the outer casing of the washing 35 machine.

In the closed position the bevelled edge 44 of the upper door fits over the bevelled edge 46 of the lower door and the doors are held in place by a latching mechanism which fits in the recess 40 formed by flanges 41 and 44 and includes wedge-shaped elements 55 which are adapted to fit into keepers 56 disposed at points substantially opposite the metal portion of the upper door.

As the keepers in the frame on both sides of the door are the same, a detailed illustration of only one has been shown. As illustrated in Figs. 2 and 3 of the drawings, stepped recesses 58 and 59 are formed in the staves in alignment with the wedges 55. Fitted in the lower recess 59 is a frame 60 having a downwardly extending flange 61 which fits in a recess 62 in the stave and is flush with the inner face of the flange 2. Flanges 63 and 64 extending outwardly from frame 60, see Fig. 5, also fit in recesses in the stave. The frame 60 may be secured in place by any suitable means, such as screws 65 which are inserted through apertures in the frame and are threaded into the stave.

A reinforcing strip 68 located above plate 3 and 60 a wedge 69 having a flange 70 extending in the recess 71 formed by step 58 below the plate, are secured to the plate 3 by means of threaded bolts passing through apertures in the superposed members, the bolts being provided with nuts 72. 65 The wedge is also provided with laterally extending reinforced flanges 73 through which set screws 74 extend so that the inclined face 75 of the wedge may be maintained in the proper position to receive the wedge-shaped elements 55. 70 Bolts 76, provided with lock nuts 77 extend through reinforcing strips 68 and the plate 3 for adjusting the wedge 69 in proper position. For instance, if it is desired to adjust the wedge downwardly, nuts 72 are loosened, the set screws 74 are adjusted upwardly a sufficient extent to lower

the front portion of the wedge to the desired extent the nuts 77 are loosened and the bolts 76 are threaded farther into the recess 71. The nuts 77 are then tightened to maintain the bolts 76 in the desired position. Wedge 69 is provided with an upwardly extending ledge 78 which is adapted to bear against the plate 3 and reinforcing strip 68.

Wedges 55 of the latching mechanism are supported adjacent the keepers by upwardly extending flanges 80 which are bifurcated and provided with plates 81. Plates 81 maintain the wedges 55 in position but permit sliding movement. The wedges 55 are preferably formed integral with bolts 85, the other end of the bolts being supported in the aperture of brackets 86 which extend upwardly from the bottom plate 40 of the upper door. The bolts 85 are provided with collars 87 and springs 88 are disposed around the bolts between brackets 86 and collars 87 which tend to force the wedges into the keepers.

A handle 88 is rotatably supported on a pivot 89 which extends through the handle and is journaled at its opposite ends in hollow bosses 90 and 91 extending inwardly from the flanges 41 and 44. A spacer 92 is interposed between the handle and the boss 91. Handle 88 is provided with a rectangular projection 93 upon which is mounted a cam 94, the opposite sides of which are provided with apertures in which the ends of links 95 and 96 are inserted and fastened. The other ends of links 95 and 96 extend into elongated openings 97 formed in bolts 85. At least one of the bolts 85 is hollow to provide a support for a spring which bears against the end of link 95. The handle 88 is provided with a post or leg 98 which engages a projection 99 extending upwardly from the bottom of plate 40. It will be particularly noted that the post 98 enables the handle to be maintained at a sufficient distance from the bottom of the recess to permit the hand of the operator to be placed over the edge of flange 44 to assist in opening the door.

When it is desired to open the door the handle 88 is moved in a clockwise direction. There will be first a small lost motion due to the elongated slot 97. Wedges 55 will then be pulled out of the keepers and the door may be opened. When the door is closed springs 88 force the wedges in position and spring 87 serves to force the links 95 and 96 to their outermost position thus maintaining the handle close to the door.

From the foregoing specification it will be apparent that I have provided an improved door construction in which the upper door serves to hold the lower door in tightly closed position against the resilient counteraction of rubber strips located along the sides of the door and in the undercut groove supported by the inclined flange of the upper door. As the resilient strip 51 is provided with flanges 52 and 53 which extend below the lower door, no crevices or openings will be present in which fabric may be caught.

It will also be apparent that by providing adjustable keepers the door may not only be maintained in tightly sealed relationship with respect to the cylinder initially but may be adjusted at intervals so that a tight fit will be obtained during the life of the cylinder.

To those skilled in the art many modifications and widely different embodiments and applications of my invention will suggest themselves without departing from the spirit and scope thereof. My disclosure and description herein

are purely illustrative and are not intended to be in any sense limiting.

What I claim is:

1. In combination, a washing machine drum having an opening in its peripheral wall and a bevelled edge member associated with said wall, a secondary door pivotally attached to the drum wall adjacent one edge of said opening on an axis parallel to the longitudinal axis of said drum, said door having an exposed bevelled surface along the full length of its free edge portion and side extensions which rest upon the adjacent walls of the cylinder when the door is closed, a main door pivotally attached to the cylinder wall adjacent the opposite edge of said opening and having the full length of its free edge provided with a bevelled surface mating that of the secondary door when both doors are in closed position, a resilient strip arranged between the bevelled edges of said doors, and latching means associated with the main door having a bevelled edge portion engageable with the bevelled edge of said member for simultaneously securing the doors in closed position and for forcing the bevelled edge of the main door inwardly toward the bevelled edge of the secondary door against the resilient action of said strip.

2. In combination, a washing machine cylinder having an opening in its cylindrical wall and a bevelled edge member associated with said wall, a secondary door pivotally attached to the cylinder wall adjacent one side edge of said opening, said door having an exposed bevelled surface along the full length of its free edge and side extensions which rest upon the adjacent walls of the cylinder when the door is in closed position, resilient strips arranged in grooves in the cylinder wall along the end edges of said opening and projecting outwardly beyond the cylinder walls, a main door pivotally attached to the cylinder wall adjacent the other side edge of said opening, said main door having side extensions which engage the resilient strips and the full length of its free edge being provided with a bevelled surface mating that of the secondary door when the doors are in closed position, a resilient strip located between said doors, and a latching mechanism associated with the main door and having a bevelled edge portion engageable with the bevelled edge of said member for simultaneously securing the doors in closed position and for forcing the doors closed against the action of all of said resilient strips.

FRANK A. GERLACH.
